HENRY C. STOLL, OF BRONX, NEW YORK, ASSIGNOR TO UNIVERSITY MANUFACTURING & SALES CO. INC., OF NEW YORK, N. Y., A CORPORATION OF NEW YORK

CIGARETTE BOX

Application filed February 9, 1929. Serial No. 338,703.

Special objects of the present invention are to provide an attractive box or case for cigarettes or the like, which may be operated to serve the cigarettes or other articles as required, which will be simple and inexpensive and which will be attractive in every way.

The foregoing and other desirable objects are attained in this invention by certain novel features of construction, combination 10 and relations of parts as set forth in the following specification.

The drawings accompanying and forming part of the specification illustrate several of the different embodiments of the invention 15 and it will be understood that the invention may be incorporated in other forms without departure from the true spirit and broad scope of the invention.

Fig. 1 is a perspective view of a form of 20 the invention designed for use on a table; Fig. 2 is an enlarged broken plan view of the same; Fig. 3 is a cross-sectional view as on substantially the plane of line 3—3 of Fig. 2; Fig. 4 is a bottom perspective view 25 of the sliding box portion of the apparatus, showing in particular the ejector cams at the back of the same. Fig. 5 is a front view of an embodiment of the invention in which the top remains stationary instead of sliding 30 with the box, as in Fig. 1; Fig. 6 is a cross-sectional view of this modified form of the invention as on substantially the plane of line 6—6 of Fig. 5; Fig. 7 is a broken sectional front elevation of a modification in 35 which the box has a swinging or rotary movement instead of a straight line sliding movement; Fig. 8 is a vertical sectional view as on substantially the plane of line 8—8 Fig. 7.

40 The device consists of but two main parts, a base 9 and a sliding or shifting box, frame, rack or tray 10.

The base has a transverse trough or channel 11, usually deeper and wider than the 45 full diameter of a standard size cigarette so that the cigarettes 12 confined within the box section will automatically drop thereinto one at a time as appears in Figs. 2 and 3.

50 Intersecting the delivery trough in the base is a channel 13, extending forwardly

from the back of the base and designed to freely receive an ejector cam or cams 14 projecting forwardly from the lower portion of the back wall 15 of the box. Two of these cams are shown in the form of inclines 55 faced toward each other, so that one or the other will be effective to eject a cigarette resting in the delivery channel depending on which way the body is shifted on the base.

In the first form of the invention shown the box is slidably confined on the base by the engagement of the cams 14 in the longitudinal slot 13 at the back of the base and by the engagement of the lower edges of the back and front walls 15, 16 with the inset shoulders or tracks 17, 18 at the back and front edges of the base. Shoulders 19 at the ends of the rearward track 17 limit the sliding movement of the box on the base. The parts may be made to fit together 60 loosely enough so that the box may be interlocked with the base by engaging it in tilted relation over the rear of the base, the inclined cams entering the slot 13 in this tilted relation until the front edge of the box 65 drops into the forward track 18 as in Fig. 3, in which position the box will be confined to the base until it is purposely tilted up at the front, so that it can be backed off the base in the reverse operation of that just 70 described. Thus the box or slide can be quickly engaged with or disengaged from the base, but will be confined thereto in easy 75 sliding relation when properly and fully engaged with the base.

A suitable cover may be provided for the box or slide, such as the removable cover 80 designated 20 in Figs. 1, 2 and 3, and this cover may have a handle such as that shown at 21 to serve as a convenient grip or finger 85 piece for use in sliding the box on the base. The removal of this cover exposes the entire interior of the box, enabling it to be readily loaded with cigarettes placed as shown 90 transversely of the base and parallel with the delivery trough. The cigarettes follow naturally one by one into this trough and the sliding movement of the box has a tendency, by engagement of the end wall of the box with the cigarettes to keep them 95 100

lined up parallel with the delivery way. Reciprocation of the box in either direction has the effect of automatically projecting a cigarette from the delivery way, as indicated in Fig. 1, through the action of one or the other of the two delivery cams. The incline of these cams is preferably relatively gradual, as indicated in Figs. 2 and 4, so as to slide the cigarettes out gradually without breaking or injuring the ends engaged by the cams.

The form of the invention illustrated in Figs. 5 and 6 differs from the form first described principally in that the cover, designated 20^a is carried by the base and remains stationary instead of being mounted upon and travelling with the box as in the first form disclosed. This cover is shown as carried by an upstanding back wall 22 attached to the back of the base by screws 23, this back wall and top being shaped and formed to harmonize generally with the base and with the sliding box 10^a. As in this construction the cover confines the box in sliding engagement on the base, there is no need for the track at the forward edge of the base, as in the first construction, and the operating handle in this case may be conveniently provided on the front of the box as indicated at 21^a. To enable the easy filling of the box, the guide slot 13 for the ejector cams may open out through one end of the base as indicated at the right in Fig. 5, where the broken lines show the box as 35 partially withdrawn for filling purposes.

In both forms described, the box or slide is an open frame and the base is a simple structure with only the transverse delivery slot and the intersecting ejector slot, so that 40 both parts may be easily and inexpensively manufactured, each in one piece, molded or otherwise shaped in metal, glass, bakelite, hard rubber, pottery, wood or other materials and the structure lends itself readily to many ornamental shapes and designs.

The same advantages are present in the third form of the invention illustrated in Figs. 7 and 8, which so far as possible has been given reference characters corresponding to those already used. In this last form of the invention, the motion is a rotary or swinging rather than a sliding one as in the first two forms, the box in this case consisting of a bell-shaped casing 10^b mounted to 45 swing on a pin 24 carried by a support 25 standing up from the forward edge of the base 9^b. The lower edge of this bell is curved to match the curvature 26 of the base and the ejector slot 13^a and cams 14^a are 50 similarly curved on arcs having their center at the pivot 24. The ejector slot may be 55 left open at one or both ends of this construction, so that the bell can be swung far enough to open up for filling as indicated 60 at the right in Fig. 7. Operating handles 65

27 may be provided on the bell or the same may be swung by direct contact with the body of the same. In the latter case, the side edges of the upstanding supporting arm 25 serve as stops for the fingers to limit 70 the swinging movements of the bell to an extent just sufficient to properly eject the cigarettes. This construction has the advantage that the bell will swing back to the intermediate position where delivery of the 75 cigarette can be effected by rocking the same one way or the other from this intermediate neutral position.

The delivery of the article is quickly and 80 easily effected by simply sliding or shifting the article holder one way or the other over the delivery way and the articles are thereby projected transversely to the line of movement into full sight and easy grasp of the 85 operator.

What is claimed is:

1. Apparatus of the character described, comprising a base adapted for placing on a table or other support, a box slidably guided on said base, said box having an inclined delivery cam projecting forwardly from the back wall of the same and the base having a delivery groove in line with said cam and opening through the front of the base below the box, said box being open at the top and bottom and a cover for said box, said cover being supported from the base in stationary relation overstanding the box.

2. Article delivery apparatus, comprising a member having an open delivery way in 100 the top of the same and a cam way intersecting the rear end of said delivery way, an article container shiftably mounted over said delivery way and an inclined delivery cam carried by said article container at the 105 back of the same and traversing the cam way aforesaid.

3. Article delivery apparatus, comprising a member having an open delivery way in 110 the top of the same, a cam way intersecting the rear end of said delivery way, an article container shiftably mounted over said delivery way, an inclined delivery cam carried by said article container at the back of the same and traversing the cam way aforesaid, said cam way being open at the back 115 of the first member to admit the cam thereinto and said cam when entered in the cam way confining the article container to said first member.

4. Article delivery apparatus, comprising a member having an open delivery way in 120 the top of the same, a cam way intersecting the rear end of said delivery way, an article container shiftably mounted over said delivery way, an inclined delivery cam carried by said article container at the back 125 of the same and traversing the cam way aforesaid and said cam way being open at one end of the first member to permit move- 130

ment of the article container sufficient to carry the cam out of the cam way.

5. Apparatus of the character described, comprising a base adapted for placing on a table or other support, a box slidingly guided on said base, said box having an inclined delivery cam projecting forwardly from the back wall of the same, the base having a delivery groove in line with said cam and opening through the front of the base below the box, said box being open at the top and bottom, a cover for said box, said cover standing in stationary relation over the box and a back wall detachably applied to the base and supporting the cover in said overstanding relation.

6. Article containing delivery apparatus, comprising a supporting base having a delivery slot in the top of the same, open at the back and at the front of the base and a cam slot in the back of the base intersecting said delivery slot, an article container movably mounted on the base and having a dependent back wall covering the back of the cam slot and delivery slot and a cam on the forward face of said back wall operating in the cam slot aforesaid.

7. Article containing delivery apparatus, comprising a supporting base having a delivery slot in the top of the same open at the back and at the front of the base, a cam slot in the back of the base intersecting said delivery slot, an article container movably mounted on the base and having a dependent back wall covering the back of the cam slot and delivery slot and reversely inclined cams projecting forwardly from the dependent portion of said back wall into said cam slot.

40 8. Article delivery apparatus, comprising a base member having a delivery way in the top of the same and open at both ends, an article holding member movable over the base member and reversely faced cams carried by said article holding member across the back open end of the delivery way to discharge articles resting therein out through the open front end of said way.

9. Article delivery apparatus comprising a member provided with a delivery way, an article holder, said holder and member being associated for lateral shifting movement one with respect to the other, said article holder covering said delivery way in all relatively shifted positions of the holder and member, and means for ejecting articles from said way.

10. Article delivery apparatus comprising a member provided with a delivery way, an article holder, said holder and member being associated for lateral shifting movement one with respect to the other, said article holder covering said delivery way in all relatively shifted positions of the holder and member, and means for ejecting articles

from said way, said delivery way opening through the front of the member and said ejecting means operating in the back end of said delivery way to thereby discharge the articles out through the front of the member.

11. Article delivery apparatus comprising a member provided with a delivery way, an article holder, said holder and member being associated for lateral shifting movement one with respect to the other, said article holder covering said delivery way in all relatively shifted positions of the holder and member, means for ejecting articles from said way, and a cover for the article holder carried by said member.

12. Article delivery apparatus comprising a base member having a delivery way in the top of the same, an article holder shiftable laterally over said base member but covering said delivery way in all positions of the same and means for ejecting articles from said delivery way during said shifting movements of the article holder over the delivery way.

13. Article delivery apparatus comprising a base member having a delivery way in the top of the same, an article holder shiftable laterally over said base member but covering said delivery way in all positions of the same and means for ejecting articles from said delivery way during said shifting movements of the article holder over the delivery way, said delivery way opening through the front of the base member and the ejecting means operating in the back of said delivery way to thereby discharge articles through the front of the base member.

14. Article delivery apparatus comprising a base member having a delivery way in the top of the same, an article holder shiftable laterally over said base member but covering said delivery way in all positions of the same, means for ejecting articles from said delivery way during said shifting movements of the article holder over the delivery way, and a cover carried by the base member and overstanding the article holder.

15. Article delivery apparatus comprising a base member having a delivery way in the top of the same and opening out through the front portion of said base member, an article holder over said base member, said article holder and base member being laterally shiftable one with respect to the other to thereby leave articles in the holder deposited in said open ended delivery way and means for ejecting said deposited articles out through the open front end of said delivery way during said relative movements of article holder and base member.

16. Article delivery apparatus comprising a base member having a delivery way in the top of the same and opening out through the front portion of said base member, an article holder over said base member, said

article holder and base member being laterally shiftable one with respect to the other to thereby leave articles in the holder deposited in said open ended delivery way and means for ejecting said deposited articles out through the open front end of said delivery way during said relative movements of article holder and base member, said ejecting means including an ejector member connected with the article holder and operating in the end of the delivery way opposite the open front end of the same.

17. Article delivery apparatus comprising a base member having a delivery way in the top of the same and opening out through the front portion of said base member, an article holder over said base member, said article holder and base member being laterally shiftable one with respect to the other to thereby leave articles in the holder deposited in said open ended delivery way and means for ejecting said deposited articles out through the open front end of said delivery way during said relative movements of article holder and base member, and a cover carried by the base member and overstanding said article holder.

18. Article delivery apparatus comprising a base member having a transversely extending article delivery trough in the top and opening out through the front of the same, an article holder laterally slidable over said article delivery trough and means actuated by said article holder for ejecting articles out the open front end of the delivery trough.

19. Article delivery apparatus comprising a member having an open ended article delivery way, a laterally shiftable article holder associated with said member to deposit articles in said open ended delivery way in the relative shifting movements of said article holder and member and means operating in the opposite end of said delivery way and actuated during said relative movement of the article holder and member to eject articles out through the open end of said delivery way.

20. Article delivery apparatus comprising a base member having a transversely extending article delivery through the top and opening out through the front of the same, an article holder laterally slidable over said article delivery trough, and means operating in the back end of said delivery way and actuated by the article holder during its movements in both directions over the delivery way to eject articles through the open front end of the delivery way.

21. Article delivery apparatus comprising a base having a longitudinally extending slot and a transversely extending delivery way, an article holder laterally shiftable over said base for depositing articles in said delivery way, said delivery way being open

through the front of the base for article discharge purposes, an article ejecting means including a member operating in said longitudinal slot for discharging articles through the open front end of the delivery way during the lateral shifting of the article holder on the base.

In testimony whereof I affix my signature.

HENRY C. STOLL.
